DESIGN FOR A BEVERAGE COOLING CABINET OR SIMILAR ARTICLE

Michael A. Martin, Erie, Pa.

Application August 19, 1938, Serial No. 79,445

Term of patent 14 years

To all whom it may concern:

Be it known that I, Michael A. Martin, a citizen of the United States, residing at Erie, in the county of Erie and State of Pennsylvania, have invented a new, original, and ornamental Design for a Beverage Cooling Cabinet or Similar Article, of which the following is a specification, reference being had to the accompanying drawing, forming a part thereof, in which:

Fig. 1 is a front perspective view of a beverage

cooling cabinet or similar article showing my design with the upper portion in closed position; and

Fig. 2 is a front perspective view thereof, with the upper portion in open position.

I claim:

The ornamental design for a beverage cooling cabinet or similar article, substantially as shown and described.

MICHAEL A. MARTIN.
